UNITED STATES PATENT OFFICE

131,299

DESIGN FOR AN ARCH BALANCER

Irwin Herskovitz, New York, N. Y.

Application October 19, 1940, Serial No. 95,927

Term of patent 7 years

To all whom it may concern:

Be it known that Irwin Herskovitz, a citizen of the United States and resident of New York, in the county of New York and State of New York, has invented a new, original, and ornamental Design for an Arch Balancer, of which the following is a specification, reference being had to the accompanying drawing, forming part thereof, in which,

Fig. 1 is a top plan view of an arch balancer embodying my new design;

Fig. 2 is a front elevational view thereof; and

Fig. 3 is a cross sectional view taken substantially on the line 3—3 of Fig. 2.

The present design is for an arch balancer characterized by its absence of a heel portion, its relatively wide transverse dimension with respect to its length, together with the concaved transverse edge adjacent the heel portion of the foot and disposed at an obtuse angle with respect to the non-flanged longitudinal edge, together with the contrasting convexed transverse edge adjacent the toe portion of the foot.

I claim:

The ornamental design for an arch balancer, substantially as shown and described.

IRWIN HERSKOVITZ.
